Patented Dec. 5, 1916.

UNITED STATES PATENT OFFICE.

LULA PENNY, OF WILSON, NORTH CAROLINA.

SEWING-MACHINE ATTACHMENT.

1,207,619.

Specification of Letters Patent.

Patented Dec. 5, 1916.

Application filed August 16, 1915. Serial No. 45,681.

To all whom it may concern:

Be it known that I, LULA PENNY, a citizen of the United States, residing at Wilson, in the county of Wilson and State of 5 North Carolina, have invented certain new and useful Improvements in Sewing-Machine Attachments, of which the following is a specification.

My invention relates to improvements in 10 sewing-machine attachments, and the main object of my invention is the provision of an attachment particularly designed for use in millinery work, for stitching closely to and securing properly the wire or cord in 15 the rim of ladies' hats.

Another object of my invention is the provision of an attachment which may be adjusted to throw the foot on either right or left of needle.

20 Another object of my invention is the provision of a presser foot with curved edges or sides making it possible to stitch close to wire or cord inside a circle.

Another object of my invention is the 25 provision of an attachment of the character and for the purposes stated which can be instantly applied and removed; which will perform its work in a rapid, efficient and practical manner and which will be very 30 simple, inexpensive and durable.

To attain the objects stated my invention consists of a sewing machine attachment embodying novel features of construction and arrangement of parts, substantially as 35 shown, described and claimed.

Figure 1 is a perspective view of the hat brim, attachment, and part of a sewing machine, showing the operation of the attachment. Fig. 2 is a perspective view of the 40 outer face of the completed or stitched hat brim, with the attachment shown in its relation to the stitching or line of threads. Fig. 3 is a top plan view of the attachment and bar to which it is attached, the bar being broken away to show the attaching 45 means. Fig. 4 is a perspective view of a portion of hat brim in which the presser foot is attached on right side of needle showing stitching close to cord on left to produce wide edge. Fig. 5 is a side elevation of the attachment and bar to which it is attached, and Fig. 6 is a front elevation thereof.

In the drawings the letter A, designates 50 the arm of the sewing machine, B the

thread, C the thread guide, D the reciprocating needle bar, E the needle carried thereby, and F the bar or post to which the presser foot is usually attached.

My device acts after the manner of the 60 presser foot and consists of the vertical arm G, having its upper end provided with a pair of kerfs H, to receive the securing screw J, to adjustably connect the attachment to the post F. The device is further 65 formed with the foot G', arranged at a right angle to the arm G and having in each edge a needle guiding recess G². In stitching wire in edge of brim the foot is adjusted to left of needle E.

In use the arm G is screwed to the post F, and the foot G², rests after the manner of the usual presser foot, upon the free edge K, of the hat brim K', the needle forming the narrow stitch L, as in Figs. 1 and 2, or 70 the wider stitch M, as in Fig. 4, and forming a hem or pocket to confine the wire or cord N. In making the narrow hem, the needle 75 would be guided in the outer recess G², while in making the wider hem the inner recess 80 G², would guide the needle and the edges of the foot G³, are preferably curved to insure the best results and the proper binding or hemming. In stitching cord in fold M, the 85 foot is adjusted to right of needle showing the bulk of hat on left or out side of machine.

It will be noted that the foot may be instantly adjusted to the right or left of the 90 needle; also that a wide or narrow hem may 95 be produced; and that the curved edges of the foot lie close to the stitching line and accommodate the curve of the brim, to secure the best results in a rapid manner.

It will thus be seen that I provide a 100 device of extremely simple and inexpensive construction, which can be quickly applied and which will prove highly efficient and desirable in millinery work, by reason of its ease of operation, rapidity and efficiency and which will prove a saving in time, labor and expense.

I claim:

1. An attachment consisting of an adjustable presser foot adapted for stitching on 105 right or left of said foot, means for adjusting said presser foot consisting of a binding screw on the presser foot bar and slots in the presser foot to be engaged by the binding screws on said presser foot bar. 110

2. In combination with the presser foot bar of a sewing machine, of an attachment secured to the presser foot bar, consisting of a foot portion having needle guides on opposite sides thereof, and an arm having slots near its upper end for adjustment to the presser foot.

5

Copies of this patent may be obtained for five cents each, by addressing the "Commissioner of Patents, Washington, D. C."

In testimony whereof I affix my signature in the presence of two witnesses.

LULA PENNY.
